UNITED STATES PATENT OFFICE.

CHARLES C. ELY AND ADOLPH KOBELT, OF KANSAS CITY, MISSOURI.

ELECTRIC TRIP MECHANISM.

SPECIFICATION forming part of Letters Patent No. 736,511, dated August 18, 1903.

Application filed October 9, 1902. Serial No. 126,422. (No model.)

To all whom it may concern:

Be it known that we, CHARLES C. ELY and ADOLPH KOBELT, citizens of the United States, residing at Kansas City, in the county 5 of Jackson, State of Missouri, have invented certain new and useful Improvements in Electric Trip Mechanism; and we do hereby declare the following to be a full, clear, and exact description of the invention, such as 10 will enable others skilled in the art to which it appertains to make and use the same.

This invention relates to electric trip mechanisms; and it has for its object a construction wherein upon closing an electric circuit a 15 weight will be dropped which in its fall may be made to operate a valve or actuate any other mechanism to start or stop an apparatus, or for any other purpose, it being understood that the invention in question may be 20 employed for whatever purpose it is applicable to.

A further object of the invention is to provide a construction wherein after the weight is dropped the actuating-current will be shut 25 off by breaking its circuit, this being accomplished automatically.

Other objects and advantages of the invention will be understood from the following description:

30 In the drawings forming portion of this specification, and in which like numerals of reference indicate similar parts in the several views, Figure 1 is an elevation showing the mechanism connected with a valve for operating the latter when the weight is dropped. Fig. 2 is a vertical section through the mechanism, parts thereof being in elevation. Fig. 3 is a section through the frame of the solenoid in a plane above the latter and showing 35 the solenoid and other parts in plan.

Referring now to the drawings, there is shown a loop-shaped frame 5, the sides of the upper portion of which are parallel and spaced sufficiently far to receive therebetween 45 a solenoid 6, the sides of this frame below the solenoid being converged and then continued parallel and slightly spaced. Within the solenoid is a slideable soft-iron core 8, which when the solenoid is energized is lifted 50 into the solenoid and when the solenoid is deenergized drops partly therefrom, the downward movement of the core being ar-

rested by contact of a terminal screw 8' with the convergent portions of the sides of the frame 5. When the solenoid is energized, the 55 core projects from the upper end thereof.

In connection with the frame 5 and other parts above described are employed two spring-arms 15, having ears 15', which are pivoted between the lower end portions 30 of 60 the frame 5, so that the arms project laterally and upwardly from the frame and also downwardly from the frame, these downwardly-directed portions being curved in opposite directions in the form of hooks 7, which lie in a 65 common plane and are so disposed that when the upper ends of the arms are moved outwardly or separated the free ends or the tips of the bills of the hooks move into contact. These hooks form clutching-jaws for engagement with the ring 19 of a weight 18, so 70 that when the jaws are in positions shown in Figs. 1 and 2 they will support the weight. The hooks or clutching jaws 7 are held in active positions by means of a toggle-lever comprising links 16 and 17, which are pivoted together at their inner ends and overlap slightly, as shown in Figs. 2 and 3, the outer 75 ends of the links being pivoted, respectively, to the upper ends of the arms 15, so that said 80 lever lies with the pivot, which connects the links directly over and in the path of movement of the solenoid-core 8. When the toggle-links are moved to the positions shown in Figs. 1 and 2, the clutching-jaws are active 85 and the arms 15 are under tension, and when the solenoid is energized and when the core 85 is raised it strikes the mutually-connected ends of the toggle-links and starts them upwardly and raises them until the jaws are 90 separated to drop the weight. To return the toggle-links to the positions shown in Fig. 2, a rod 13 is provided, which is passed slidably through perforations in the end pieces or spool of the solenoid, the upper end of this 95 rod being turned laterally and terminating in an eye 12, which slidably engages the rod 11, connected to the frame 5 and to the end of the solenoid-spool. This laterally-turned upper end portion of the rod 13 extends transversely of the toggle-links above and near to the connecting-pivot thereof, and when the inner ends of the links are moved upwardly 100 by the solenoid-core the rod is lifted. To

2
return the links then, it is necessary only to draw the rod downwardly.

It is desirable to break the energizing-circuit of the solenoid as soon as the weight has been dropped, and for this purpose two electrical contacts 26 and 27 are mounted upon the end of the solenoid-spool in such position that when the toggle-links are set, as illustrated in Fig. 2, the link 17 will bridge the contacts and close the circuit therebetween. The contact 26 is connected with one end of the solenoid-winding, while the other contact, 27, has a binding-screw 28 for connection of a line-wire, the second terminal or end of the solenoid-winding being connected with a binding-screw 25 for attachment of a second line-wire. When the toggle-links are moved upwardly by the action of the solenoid-core, the link 17 moves out of engagement with the contacts 26 and 27 and the circuit is broken. The weight in its tendency to move from the clutching-jaws forces the jaws apart and the upper ends of the arms toward each other, so that the link 17 is carried positively from engagement with the contact. The weight is shown as connected by means of a cord 30 with a cut-off valve 31, the weight passing over a pulley 32, so that when the weight is dropped the valve will be operated.

30 What is claimed is—

1. A device of the class described comprising a solenoid having a reciprocatory core, coöperating clutch-jaws, and means for holding the clutch-jaws in operative position, said holding means lying in the path of movement of the core for engagement and movement thereby into inoperative position.
2. A device of the class described comprising a solenoid having a reciprocatory core, a toggle-lever disposed for movement of its links to break the lever by engagement therewith of the core when the solenoid is energized, a weight-clutch operatively connected with the toggle-lever, and electrical contacts 40 in spaced relation and disposed for simultaneous contact by a toggle-link when the toggle-lever is in position for engagement by

the core, said contacts being included in the circuit of the solenoid.

3. A device of the class described comprising a solenoid having a reciprocatory core, a circuit-breaker for the solenoid disposed for actuation by the core when the solenoid is energized, and a clutch mechanism disposed for actuation by the core prior to breaking 55 of the solenoid-circuit.

4. A device of the class described comprising a solenoid having a reciprocatory core, pivoted arms having clutching-jaws to receive and hold a weight, and a toggle-lever 50 having its links pivoted respectively to the arms and adapted to hold the arms with their jaws in engaging positions, said links lying in the path of movement of the core for engagement thereby to release the arms and their 65 jaws.

5. A device of the class described comprising a solenoid having a reciprocatory core, pivoted arms having clutching-jaws to receive and hold a weight, a toggle-lever having its links pivoted respectively to the arms and adapted to hold the arms with their jaws in engaging positions, said links lying in the path of movement of the core for engagement thereby to release the arms and their 75 jaws, and means for returning the links to their normal positions.

6. A device of the class described comprising a solenoid having a reciprocatory core, pivoted arms having coöperating clutching-jaws at one end, a toggle-lever having its links pivoted to the opposite ends of the arms and lying in the path of movement of the core, for actuation thereby to move the arms and separate their jaws and means for returning the toggle-lever to its normal position.

In testimony whereof we affix our signatures in presence of two witnesses.

CHARLES C. ELY.
ADOLPH KOBELT.
